PORATION OF PENNSYLVANIA

SHOCK-ABSORBING CARRIER-ROD STOP MECHANISM FOR FULL-FASHIONED KNITTING
MACHINES

Application filed January 24, 1929. Serial No. 334,641.

Our invention relates to full fashioned knitting machines, and more particularly to improved thread-carrier rod operating mechanism therefor, our main object being 5 to provide improved means for determinedly arresting the reciprocative travel of said rods by means of novel momentum-absorbing stop mechanism adapted to gradually reduce the speed of the moving rod as it approaches its fixed stop position.

Such momentum-absorbing stop of the carrier rods is particularly essential when high operating speeds are desired, and various devices for this purpose have heretofore 15 been attempted.

Our improvements provide a novel and simplified structure especially effective in operation, readily applied to the ordinary knitting machine, adjustable with the usual narrowing screw mechanism, and of economical cost of attachment.

Our invention comprises the mechanism hereinafter more fully described in connection with the drawings accompanying the 25 same and forming part thereof, the novel features of which are specifically set forth in the appended claims.

Fig. 1 is a partial rear view of a full fashioned knitting machine indicating mainly the central coulier motion mechanism and the end narrowing head mechanisms, with the intermediate portions omitted and the narrowing heads closed in toward said coulier mechanism such parts particularly involving and being sufficient to fully disclose the application to said known machine of a preferred embodiment of our improved momentum absorbing rod stop mechanisms.

Fig. 2 is a partly diagrammatic fragmentary view of the frictionally operated thread carrier rods as controlled by our mechanism.

Fig. 3 is a much enlarged cross sectional view through the center bed portion of the machine showing certain details of our carrier rod reciprocative and control mechanism.

Fig. 4 shows, on a much enlarged scale, the end portion of the machine indicated to the left in Fig. 1.

50 Figs. 5, 6, 7 and 8 are diagrammatic views

indicating successive steps of our rod stop mechanism during a half cycle of machine operation.

The knitting machine shown in the drawings is of usual construction and well known 55 operation and the fragmentary portions thereof indicated comprise the intermediate-located coulier motion mechanism embracingly marked 10, which oscillates a lever 11, the free end of the latter being connected by a link 12 to a slidable bracket 13; slide rod 14 and sliding slur cock bar 15 being connected to said bracket 13 and receiving joint reciprocative movements imparted by said coulier motion 10, as heretofore. Slide rod 60 60

14 is provided with a usual plurality of friction boxes 16, each normally traversed with said rod but slidably thereon when held against movement, and each friction box carries a slide bolt 17 movable into engagement with a dog 18 on a selected one of a plurality of slidably mounted thread-carrier rods 19, such connected rod 19 then being reciprocated in unison with said slide rod 14 and slur cock bar 15 as usual. The carrier rods 65 65

19 extend the full length of the machine and carry a series of thread guides 20 to lay the threads in place for action of the several needle sections in known manner, and their reciprocative travel has heretofore been commonly controlled by their abrupt contact against fixed stops 21 mounted on the carrier nuts 22 of adjusting screws 23 of the known end narrowing head mechanisms indicated in 70 70

Fig. 1.

The above mechanism thus briefly described is old, but an understanding thereof is necessary to a full disclosure of our invention which relates to improved stop control means for said thread carrier rods, their heretofore abrupt contact against the usual end stops, especially in high speed machines, resulting in unnecessary noise, destructive wear of the necessarily delicately adjusted variable control mechanism, and inaccuracies of the 80 80

thread feed due to rebound of the carrier rods from said stops.

Our improved rod stop mechanisms must operate at each end of the rod reciprocative travel, and certain parts thereof associated 90 90

95

100

with the usual narrowing head mechanisms are therefore merely duplicated, one acting at the right hand end, and the other on the left hand end of the machine. It is accordingly thought that a full description of the mechanism at one end will suffice for an understanding of the construction and operation of the duplicate mechanism at the opposite end, and the similar parts of the respective ends bear the same reference characters, except those at the right hand end have the exponent "a" added.

In the preferred embodiment of our invention shown in the drawings we indicate an engaged slide rod 19 as controlled indirectly through its operative friction box 16, and for this purpose employ a stop rod 25 extending lengthwise of the machine and freely slidable in carrying bosses 26 formed on the series of friction boxes, its free right hand end extending beyond the last friction box and its opposite left hand end being pivotally connected to one end of a controlling bell crank 27 hereinafter more fully described. The similar right hand rod 25^a is shown as lying in parallel relation to rod 25 and slidably carried in the same bosses 26 of said friction boxes 16, 16, its left end being free and its right end pivoted to a similar controlling bell crank 27^a. The rod 25, as shown, is provided with a tension spring 28, one end of the latter being connected to a collar 29 fixed to said rod and its opposite end held by a post 30 on a sleeve 31 slidable on a supporting shaft 132, said sleeve being movable on said shaft through fixed connection to carrier nut 22 as shown. Said rod 25 also carries a series of stop collars 32, for convenience one being provided for each friction box, only those however for active carrier-rod-engaged friction boxes being required, and these are adjustably positioned and fixedly clamped to said rod so as to engage at the proper time with their respective friction box bosses 26 as will be more fully described hereinafter.

Slur cock bar 15, is slidably supported as heretofore by brackets 37 fixed to the center bed beam 38, and to such end of said bar we secure as by bolts 39, extensions 40, 40^a projecting beneath bell crank 27, 27^a, and preferably firmly supported and slidably movable on anti-friction rollers 41, 41^a mounted in a frame 42, 42^a fixedly carried by brackets 43, 43^a secured to center bed beam 38, said frame having a projecting ledge 44, 44^a, and said slur cock extension having end cams 45, 45^a, the purpose of both of which will appear later.

Controlling bell crank 27 is pivotally mounted on a stud shaft 50, one end of the latter being fixedly secured to carrier nut 22 as shown, and the opposite end thereof is firmly held by a bracket 51 the lower end of which projects beneath frame ledge 44 and slidably engages the latter as stud 50 moves

with carrier nut 22, an adjustable wear strip 52, as shown, being preferably provided between said projection and ledge.

One end of said bell crank 27, as previously described, is pivotally connected to stop rod 25, and its opposite end, as shown, carries an anti-friction roller 55 adapted to ride on slur cock extension 40 and its end cam 45, the projecting fixed pivot pins 56 for said roller preferably having secured thereto a stop nut 57 having a nicely adjustable headed bolt extension 58 adapted to seat on the upper surface of the aforesaid frame ledge 44 and accurately control the swing of said bell crank 27 and its pivotally connected stop rod 25, so the friction-box engaged stop collars 32 on said rod will hold said friction boxes against movement as their connected rods slowly come to rest against the usual end stops 21.

By referring now more particularly to Figs. 5 to 8 inclusive, it will be seen that these views diagrammatically indicate various positions of a single thread carrier rod with its operative friction box and our improved momentum absorbing rod stop mechanism therefor during a half cycle of operation, no attempt being made to show correct size or proportion of the various parts thus illustrated.

In Fig. 5 the jointly reciprocated slide bar 14 and slur cock bar 15 with its end cams 45 are shown as at the extreme right end of their travel and beginning reverse movement toward the left end of the machine as indicated by the arrow. Friction box 16 on rod 14 is moving jointly with the latter, and guide rod 19, the dog 18 of which is shown engaged by the bolt 17 of said friction box is being moved to the left by said friction box, and away from end stop 21^a which has determined its travel to the right, irrespective of the fixed travel of slide rod 14. Stop rod 25 is loosely sliding in its friction box boss 26, said rod being held immovable by its bell crank 27, the bolt extension 58 on one arm of the latter resting on fixed ledge 44. Right stop rod 25^a is restrained against movement by its spring 28^a, and is freely sliding in said boss 26, and its collar 32^a is behind said boss and has no restraining effect on the latter.

As the parts above set forth progress in their travel they will assume the position illustrated in Fig. 6, slide rod 19 having travelled away from stop 21^a, and slur cock cam 45^a passing under the roller of bell crank 27^a to swing the latter, such action merely idly moving stop rod 25^a to the left.

Further progress as illustrated in Fig. 7 has brought slur bar cam 45 beneath left bell crank 27, its advancing face first moving rod 25 to the right, and its inward inclined face permitting reverse movement of said rod as the roller rides down the same. Friction box

16 has moved into contact engagement with adjustably set rod collar 32 such engagement taking place while said rod 25 is moving to the left as roller 55 rides down the cam face. 5 Guide rod 19 has almost reached its end stop 21, and the shape of cam 45 controlling the movement of rod 25 thus acts to slow the movement of its collar engaged friction box causing the latter to slide on rod 14, thus 10 simultaneously effecting the same action on friction box engaged guide rod 19.

Fig. 8 shows final movement to the left, the rod 19 is now at rest against stop 21 and stop rod 25 is also at rest as bolt extension 58 15 now rests on ledge 44.

Similar operations occur during reverse movements of the above reciprocated parts back to the position indicated in Fig. 5, and need no repetitious description.

20 To accomplish our stated purpose of avoiding shock in arresting the movement of rod 19, the proper shape of cam 45 is an important factor. The advancing face 145 of said cam is unimportant as its action takes place 25 to move rod 25 when its stop collar 32 is beyond the range of engagement with the boss 26 of friction box 16, such movement merely setting the roller of bell crank 27 at the upper end of the important inward cam face 245, 30 which face controls downward movement of said rollered end and consequently movement of rod 25 coincidentally with the moving friction box.

As indicated most clearly in Fig. 4, the 35 concave cam face 245 is so shaped that the upper end thereof is practically on a straight line, inclined at an angle of forty-five degrees, with the lower continuation thereof gradually curving until it tangentially meets the 40 surface of slur bar extension 40. By properly setting stop collar 32 on rod 25, this cam will act on said rod through controlling bell crank 27, due to roller 55 riding down the inward cam face 245, so as to first move said 45 collar 32 at approximately the same speed as the friction box 16, the rod boss 26 of which at the beginning of said roller movement down said cam has practically reached contact engagement with said stop collar. Actual 50 contact of said boss and stop gently occurs as the roller rides into the lower curved portion of cam face 245, which face gradually acts to bring said bell crank to a stop as the roller rides on to flat surface of slur bar 55 extension 40, such gradual stop of said bell crank acting to slow the movement of rod 25 to a stop, consequently gently bringing friction box 16 to a stop against collar 32 with ease and no danger of rebound. Spring 28 60 insures engagement of roller 55 with cam 45, and bolt extension 58 may be nicely adjusted so that guide rod 19 may be stopped by our momentum absorbing mechanism above set forth just as it reaches its fixed stop 21, or 65 the latter may be omitted entirely our mech-

anism providing all necessary control of said rod and being capable of very fine adjustment.

As previously described the bell crank stud shaft 50 and sleeve 31 are fixed to and movable with carrier nut 22 so that as the latter is moved by its adjusting screw 23, operated as heretofore in well known manner, to move end stop 21 for fashioning the fabric, bell crank 27 will move equally, its pivotally connected stop rod 25 being accordingly shifted in its friction box bosses 26 so that the action of rod collar 32 will always remain in fixed relation to stop 21 for timed cooperative action therewith.

Having thus fully set forth the nature of our invention and the manner of its operation, we do not desire to limit ourselves to the preferred construction specifically shown and described, as modifications may be readily devised within the scope of our invention as defined in the following claims.

What we claim is:

1. In a full fashioned knitting machine having a thread-carrier rod and means for reciprocatively operating the same, a momentum-absorbing rod-stop mechanism comprising a longitudinally movable stop rod for said reciprocated carrier rod periodically engageable with the latter, and means operated by said carrier rod reciprocative means to progressively decrease the speed of said stop rod longitudinal movement to a full stop during said periodical carrier rod engagement.

2. In a full fashioned knitting machine having a thread-carrier rod, means for reciprocatively operating the same, and a narrowing nut for varying the reciprocative movements of said carrier rod, a momentum-absorbing rod-stop mechanism movable with said narrowing nut and comprising a longitudinally movable stop rod for said reciprocated carrier rod periodically engageable with the latter, and means operated by said carrier rod reciprocative means to control said stop rod longitudinal movement during said periodical carrier rod engagement.

3. In a full fashioned knitting machine having a thread-carrier rod, reciprocative mechanism therefor comprising a slide rod, and frictional means engaging said carrier and slide rods, a momentum-absorbing rod-stop mechanism for said carrier rod comprising a longitudinally movable stop rod engageable with said frictional means, a slide bar movable with said slide rod and means actuated by said slide bar to control the longitudinal movement of said stop rod during engagement therewith of said frictional means.

4. In a full fashioned knitting machine having a thread-carrier rod, reciprocative mechanism therefor comprising a slide rod, and frictional means engaging said carrier

and slide rods, a momentum-absorbing rod-stop mechanism for said carrier rod comprising a stop rod engageable with said frictional means, operative means to limitedly move said stop rod longitudinally, and a slide bar movable with said slide rod and having means engaging said stop rod operative means to control the longitudinal movement of the latter during engagement there-with of said frictional means.

5 5. In a full fashioned knitting machine having a thread-carrier rod, reciprocative mechanism therefor comprising a slide rod, and frictional means engaging said carrier and slide rods, a momentum-absorbing rod-stop mechanism for said carrier rod comprising a stop rod engageable with said frictional means, a bell-crank to limitedly move said stop rod longitudinally, and a slide bar 15 movable with said slide rod and having a cam engaging said bell-crank to control the longitudinal movement of said stop rod during its engagement with said frictional means.

20 6. In a full fashioned knitting machine having a thread-carrier rod, reciprocative mechanism therefor comprising a slide rod, a frictional device connecting said carrier and slide rods, and a narrowing screw mechanism to vary successive carrier-rod reciprocations, a momentum-absorbing rod-stop mechanism for said carrier rod controlled by said narrowing screw mechanism and comprising a longitudinally movable stop 25 rod engageable with said frictional devices, and a slide bar movable with said slide rod and operative on said stop rod to control the longitudinal movement of the latter during engagement therewith of said frictional 40 devices.

25 7. In a full fashioned knitting machine having a thread-carrier rod, a reciprocative mechanism therefor comprising a slide rod, a frictional device connecting said carrier and slide rods, and a narrowing screw mechanism to vary successive carrier-rod reciprocations, a momentum-absorbing rod-stop mechanism for said carrier rod movable with by said narrowing screw mechanism and comprising a 30 stop rod engageable with said frictional device, operative means to limitedly move said stop rod longitudinally, and a slide bar movable with said slide rod and actuating said stop rod operative means to control longitudinal movement of the latter during engagement therewith of said frictional devices.

35 8. In a full fashioned knitting machine having a thread-carrier rod, reciprocative mechanism therefor comprising a slide rod, a frictional device connecting said carrier and slide rods, and a narrowing screw mechanism to vary successive carrier-rod reciprocations, a momentum-absorbing rod-stop mechanism for said carrier rod movable with 40 by said narrowing screw mechanism and com-

prising a stop rod engageable with said frictional device, a bell-crank to longitudinally move said stop rod, and a slide bar movable with said slide rod and having a cam engageable with said bell-crank to control the longitudinal movement of said stop rod during engagement therewith of said frictional device.

9 9. In a full fashioned knitting machine having a thread-carrier rod, means to reciprocate the same, a momentum-absorbing rod-stop mechanism for said carrier rod comprising a stop rod, a bell crank for actuating the same, and a cam carried by said reciprocative means to operate said bell crank; a fixed rest for one end of said bell crank and an adjustable stop on the latter adapted to seat on said rest.

10 10. In a full fashioned knitting machine having a thread-carrier rod, means to reciprocate the same, a momentum-absorbing rod-stop mechanism for said carrier rod comprising a stop rod, a bell crank for actuating the same, and a cam carried by said reciprocative means to operate said bell crank; a fixed rest for one end of said bell crank, an adjustable stop on the latter adapted to seat on said rest, and resilient means to hold said stop on said rest.

95 11. In a full fashioned knitting machine having a thread-carrier rod, reciprocative mechanism therefor, and frictional means connecting said rod to said reciprocative mechanism, a momentum-absorbing rod-stop mechanism for said rod comprising a stop rod, bosses on said friction means adapted to slidably support said stop rod, an adjustably fixed stop on said stop rod engageable with a determined boss, and stop rod operating mechanism including a reciprocally mounted cam and a stop rod connected member rideable on said cam, the reciprocation of the latter being actuated by said carrier rod reciprocative mechanism.

100 12. In a full fashioned knitting machine having a thread-carrier rod, reciprocative mechanism therefor, and a narrowing nut adapted to vary said rod reciprocations, a momentum-absorbing rod-stop mechanism comprising a stop rod having a limited movement with said rod, a bell crank actuating said rod, and means carried by said carrier rod reciprocative means adapted to operate said bell crank; a stud shaft for said bell crank having one end engaging said narrowing nut, a slide support for its opposite end, and a fixed slide way for the latter.

105 In testimony whereof we affix our signatures.

CHRISTIAN F. MEYER. 125
GOTTLOB BITZER.
